(57) **CLAIM**

The ornamental design for a pillow, as shown and described.

DESCRIPTION

FIG. 1 is a front, right, top perspective view of a pillow, showing my new design;

FIG. 2 is a rear, bottom, left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view of the pillow in a detached state;

FIG. 10 is a rear, bottom, left perspective view of the pillow in a detached state;

FIG. 11 is a partial enlarged view of FIG. 9; and,

FIG. 12 is a partial enlarged view of FIG. 10.

The dashed broken lines in the figures are for the purposes of illustrating portions of the pillow and form no part of the claimed design.

The dash-dot-dash broken lines are for notating enlarged views and form no part of the claimed design.

1 Claim, 12 Drawing Sheets
